CLAIM

The ornamental design for a drill, as shown and described.

DESCRIPTION

FIG. 1 is a front perspective view of a drill according to the invention.

FIG. 2 is a front view of the drill of FIG. 1.

FIG. 3 is a rear view of the drill of FIG. 1.

FIG. 4 is a right side view of the drill of FIG. 1.

FIG. 5 is a left side view of the drill of FIG. 1.

FIG. 6 is a top plan view of the drill of FIG. 1; and, FIG. 7 is a bottom plan view of the drill of FIG. 1.

The broken lines shown in the drawings do not form any part of the claimed design.
